UNITED STATES PATENT OFFICE

FREDERICK J. ZIMMERER, OF MIDDLETOWN, CONNECTICUT, ASSIGNOR TO THE RUSSELL MANUFACTURING COMPANY, OF MIDDLETOWN, CONNECTICUT, A CORPORATION OF CONNECTICUT

DESIGN FOR A WEBBING FOR SUSPENDERS, GARTERS, AND SIMILAR ARTICLES

Application filed April 5, 1930. Serial No. 35,168. Term of patent 3½ years.

To all whom it may concern:

Be it known that I, FREDERICK J. ZIMMERER, a citizen of the United States, and a resident of Middletown, in the county of Middlesex and State of Connecticut, have invented a new, original, and ornamental Design for Webbing for Suspenders, Garters, and Similar Articles, of which the following is a specification, reference being had to the accompanying drawings, forming part thereof, in which the figure is a face view of a piece of webbing embodying my invention.

I claim:

The ornamental design for webbing for suspenders, garters and similar articles, as shown.

FREDERICK J. ZIMMERER.
